UNITED STATES PATENT OFFICE.

ERNEST NELSON HUMPHREY, OF NEW BRITAIN, CONNECTICUT.

BUCKLE.

Application filed September 1, 1922. Serial No. 585,607.

To all whom it may concern:

Be it known that I, ERNEST NELSON HUMPHREY, a citizen of the United States of America, residing at New Britain, Connecticut, have invented a new and useful Buckle, of which the following is a specification.

My invention relates to improvements in buckles of a type particularly useful in connection with belts for personal wear. It is essentially an improvement on the buckle set forth and described in my former Patent No. 1,395,713 of November 1, 1921.

In the drawings:

15 Figure 1 is a perspective view of the rear side of the buckle showing the belt ends in operative relation therewith.

Fig. 2 is a longitudinal section through the center of the buckle and belt with the parts 20 in the same position as indicated in Fig. 1.

Fig. 3 is a similar view, the parts being shown in a different position.

Fig. 4 is a perspective view of the buckle with the belt ends detached.

25 Fig. 5 is a view similar to Fig. 3, illustrating a modification.

Fig. 6 is a perspective view of certain details shown in Fig. 5.

1 represents a front plate having rearwardly extending flanges 2-2 at the upper and lower edges forming a channel between them for the passage of the belt. 3 is a plate pivoted at 4-4 to the flanges 2-2 at the back of plate 1. At the outer end of plate 35 3 is pivoted another plate 5. 6-6 are belt gripping teeth which are bent off from the plate 5 at an angle, as shown, which teeth co-act with the adjacent part of the plate 3 in fixedly securing one end of the belt to 40 the buckle. The other end of the plate 5 is provided with offset portions 7-7, which in this case are in the form of lugs or ears, and pivotally mounted between the ears 7-7 is what I will term a movable

45 cam 8, which functions to frictionally grip the sliding end of the belt between itself and the back of plate 1, as best seen in Fig. 2, wherein the fixed end of the belt is indicated at 9 and the adjustable end at 10. In this view the compressing effect of the movable cam 8 on the adjustable end 10 of the belt is exaggerated for the purposes of illustration. The belt engaging portion of the movable cam 55 8 is preferably eccentric so that, as tension

on the belt increases, the cam may turn so as to increase its gripping action thereon. Furthermore, by this formation belts of substantially different thicknesses may be taken care of the eccentric cam action.

60 To assemble the parts, the end 9 of the belt is first secured to the plate 3 by swinging the plate 5 from the position indicated in

Fig. 4 to that indicated in Figs 2 and 3, so that the teeth 6 will firmly engage the end 9 of the belt and hold it fixedly in place. To insert the adjustable end 10 of the belt the same is passed through the channel between the flanges 2-2 and thence through the

space between the end of the plate 3 and the 70 back of plate 1, as shown in Fig. 3. The several parts are then swung from the position indicated in Fig. 3 to that indicated in

Fig. 2 which serves to move the cam into the belt gripping position in the same manner as indicated in my former patent, but

in the present instance the cam 8 serves as a self-adjusting means to compensate for belts of different thicknesses. To release the 75 adjustable end 10 of the belt the several parts are swung back to the position indicated in

Fig. 3 which movement withdraws the cam 80 from belt holding engagement.

I have shown my invention in its preferred form and in the use of the terms to designate various parts, such as the term

“plate”, I have used the same in a broad sense. While I have shown the belt gripping portion of the plate 5 which engages

the fixed end 9 of the belt in the form of 90 prominent teeth, I do not desire to be limited to this specific structure, as it is entirely possible that a plain edge or a slightly knurled edge would very satisfactorily engage and hold the belt end 9.

95 In the modification shown in Figs. 5 and 6, 5^a represents a plate corresponding to the plate 5 in the previous views, but in this case I have provided a loop 5^b at the rear end of the plate as the means for receiving the fixed end of the belt, which may be folded through said loop and stitched or otherwise fastened. In all of these cases the particular tension of the gripping member may be adjusted or varied, by bending the plate 5, which carries the gripping element.

100 It should be understood that, while I have shown the pivot ends 4 as formed integrally with the plate 3, the particular construction of these and any other pivots is immaterial,

105

110

that is to say, it is obvious that said pivots may be either integral or non-integral, as desired.

What I claim is:

- 5 1. In a buckle, a front plate, a second plate pivotally connected to the back of the front plate and spaced apart therefrom, a third plate pivotally connected adjacent the free end of the second plate, with means co-
10 acting with said second plate to secure the buckle fixedly to one end of a belt, a movable cam adjacent the free end of said third plate and carried thereby and located adjacent to the pivotal portion of said second plate when in operative position.
- 15 2. In a buckle, a front plate, a member pivotally connected thereto at the back and spaced apart therefrom, another member pivotally connected adjacent the free end of
20 said first member with means carried thereby to fixedly secure one end of a belt between said members, a movable cam adjacent the free end of the last mentioned member and carried thereby and located at one side of
25 the pivotal portion of said first member when said cam is in the belt engaging position.
- 30 3. In a buckle, a front plate, a member hinged to and at the back thereof and spaced apart therefrom to form a belt passage, means carried by said member to fixedly secure one end of a belt thereto, a movable cam carried by said means and located between the pivotal portion of the first member and the back of said front plate when the several parts are in the belt engaging position.
- 35 4. In a buckle, a front plate, a member hinged to and at the back thereof and spaced apart therefrom to form a belt passage, means carried by said member to fixedly secure one end of a belt thereto, a movable cam carried by said means and located between the pivotal portion of said hinged member and the back of said front plate when the several parts are in the belt engaging position, said cam being bodily withdrawn from said operative position by swinging the hinged member away from said front plate.
- 40 5. In a buckle, a front plate, a member pivoted at one end to the back of said plate and spaced apart therefrom, a second member pivoted to the free end of the first-mentioned member, a cam pivoted at one end of the second-mentioned member, and attaching means at the opposite end of said second-mentioned member for receiving one end of the belt, the other end of said belt being slideable through the space between said plate and the other named parts when the same are in one position, and being held in place against sliding by said cam, when the parts are in another position.
- 45 6. In a buckle, a front plate, a member pivoted at the back of said plate and spaced apart therefrom, means carried by said member and movable relatively thereto, and a cam pivotally mounted on said movable means independently of said pivoted member, said cam being bodily movable toward and away from the pivotal portion of the first mentioned member.
- 50 7. In a buckle, a front plate, a member pivoted at the back of said plate and spaced apart therefrom, another member pivoted to the free end of the first member, a cam pivoted to the last-mentioned member and positioned adjacent to the pivotal portion of the first-mentioned member when said two members are folded together, and means adjacent the pivotal portion of the second-mentioned member for securing one end of a belt thereto, the other end of said belt being adjustably engaged between said front plate and said cam when the parts are in one position and being free to slide between said plate and cam when said parts are in another position.
- 55 8. In a buckle, a front plate, a member pivoted at the back of said plate and spaced apart therefrom, another member pivoted to the free end of the first member, a cam pivotally mounted on said movable means independently of said pivoted member, said cam being bodily movable toward and away from the pivotal portion of the first mentioned member, and also being bodily movable into and out of position between the front plate and the pivotal portion of said pivoted member.
- 60 9. In a buckle, a front plate, a member pivoted at the back of said plate and spaced apart therefrom, another member pivoted to the free end of the first member, a cam pivotally mounted on said movable means independently of said pivoted member, said cam being bodily movable toward and away from the pivotal portion of said pivoted member, and positioned adjacent to the pivotal portion of the first-mentioned member when said two members are folded together, and means adjacent the pivotal portion of the second-mentioned member for securing one end of a belt thereto, the other end of said belt being adjustably engaged between said front plate and said cam when the parts are in one position and being free to slide between said plate and cam when said parts are in another position.
- 65 10. In a buckle, a front plate, a member pivoted at the back of said plate and spaced apart therefrom, another member pivoted to the free end of the first member, a cam pivotally mounted on said movable means independently of said pivoted member, said cam being bodily movable toward and away from the pivotal portion of the first mentioned member, and positioned adjacent to the pivotal portion of the first-mentioned member when said two members are folded together, and means adjacent the pivotal portion of the second-mentioned member for securing one end of a belt thereto, the other end of said belt being adjustably engaged between said front plate and said cam when the parts are in one position and being free to slide between said plate and cam when said parts are in another position.
- 70 11. In a buckle, a front plate, a member pivoted at the back of said plate and spaced apart therefrom, another member pivoted to the free end of the first member, a cam pivotally mounted on said movable means independently of said pivoted member, said cam being bodily movable toward and away from the pivotal portion of the first mentioned member, and positioned adjacent to the pivotal portion of the first-mentioned member when said two members are folded together, and means adjacent the pivotal portion of the second-mentioned member for securing one end of a belt thereto, the other end of said belt being adjustably engaged between said front plate and said cam when the parts are in one position and being free to slide between said plate and cam when said parts are in another position.
- 75 12. In a buckle, a front plate, a member pivoted at the back of said plate and spaced apart therefrom, another member pivoted to the free end of the first member, a cam pivotally mounted on said movable means independently of said pivoted member, said cam being bodily movable toward and away from the pivotal portion of the first mentioned member, and positioned adjacent to the pivotal portion of the first-mentioned member when said two members are folded together, and means adjacent the pivotal portion of the second-mentioned member for securing one end of a belt thereto, the other end of said belt being adjustably engaged between said front plate and said cam when the parts are in one position and being free to slide between said plate and cam when said parts are in another position.
- 80 13. In a buckle, a front plate, a member pivoted at the back of said plate and spaced apart therefrom, another member pivoted to the free end of the first member, a cam pivotally mounted on said movable means independently of said pivoted member, said cam being bodily movable toward and away from the pivotal portion of the first mentioned member, and positioned adjacent to the pivotal portion of the first-mentioned member when said two members are folded together, and means adjacent the pivotal portion of the second-mentioned member for securing one end of a belt thereto, the other end of said belt being adjustably engaged between said front plate and said cam when the parts are in one position and being free to slide between said plate and cam when said parts are in another position.
- 85 14. In a buckle, a front plate, a member pivoted at the back of said plate and spaced apart therefrom, another member pivoted to the free end of the first member, a cam pivotally mounted on said movable means independently of said pivoted member, said cam being bodily movable toward and away from the pivotal portion of the first mentioned member, and positioned adjacent to the pivotal portion of the first-mentioned member when said two members are folded together, and means adjacent the pivotal portion of the second-mentioned member for securing one end of a belt thereto, the other end of said belt being adjustably engaged between said front plate and said cam when the parts are in one position and being free to slide between said plate and cam when said parts are in another position.
- 90 15. In a buckle, a front plate, a member pivoted at the back of said plate and spaced apart therefrom, another member pivoted to the free end of the first member, a cam pivotally mounted on said movable means independently of said pivoted member, said cam being bodily movable toward and away from the pivotal portion of the first mentioned member, and positioned adjacent to the pivotal portion of the first-mentioned member when said two members are folded together, and means adjacent the pivotal portion of the second-mentioned member for securing one end of a belt thereto, the other end of said belt being adjustably engaged between said front plate and said cam when the parts are in one position and being free to slide between said plate and cam when said parts are in another position.
- 95 16. In a buckle, a front plate, a member pivoted at the back of said plate and spaced apart therefrom, another member pivoted to the free end of the first member, a cam pivotally mounted on said movable means independently of said pivoted member, said cam being bodily movable toward and away from the pivotal portion of the first mentioned member, and positioned adjacent to the pivotal portion of the first-mentioned member when said two members are folded together, and means adjacent the pivotal portion of the second-mentioned member for securing one end of a belt thereto, the other end of said belt being adjustably engaged between said front plate and said cam when the parts are in one position and being free to slide between said plate and cam when said parts are in another position.

ERNEST NELSON HUMPHREY.
